UNITED STATES PATENT OFFICE

113,509

DESIGN FOR A LIGHTING UNIT

Carl F. Haas, Cleveland, Ohio, assignor to Westinghouse Electric & Manufacturing Company, a corporation of Pennsylvania

Application December 17, 1937, Serial No. 73,688

Term of patent 14 years

To all whom it may concern:

Be it known that I, Carl F. Haas, a citizen of the United States, residing in Cleveland, in the county of Cuyahoga and State of Ohio, have invented a new, original, and ornamental Design for a Lighting Unit, of which the following is a specification, reference being had to the accompanying drawings, forming a part thereof, wherein:

Fig. 1 is a side elevational view of a lighting unit showing my new design,

Fig. 2 is a top plan view thereof,
Fig. 3 is a side elevational view of the opposite side to that shown in Fig. 1, and
Fig. 4 is an end view of the unit.

I claim:

The ornamental design for a lighting unit, substantially as shown.

CARL F. HAAS.
